UNITED STATES PATENT OFFICE

CHARLES POWELL, OF LOS ANGELES, CALIFORNIA

GRIPPING DEVICE

Application filed May 28, 1928. Serial No. 281,272.

This invention relates to improvements in apparatus to facilitate the handling of well casing, tubing, or drill pipe sections as they are being lowered or elevated with respect to the well.

The primary object of this invention is the provision of improved well drilling apparatus embodying novel means to automatically operate the slip apparatus upon a rotary drilling table in such a relation as to permit the expeditious and efficient removal of pipe sections or the placement thereof with respect to the well.

A further object of this invention is the provision of improved apparatus to facilitate the removal of tubing, casing, or drill pipe sections with respect to the well, in such a relation that the gripping slips will be automatically operated to grip a section should there be an accidental lowering of the string of tubing or casing into the well.

A further object of this invention is the provision of improved slip grip operating means for well drilling apparatus, embodying means operable by the elevator at the end of the lowering of a section into the well to cause a grip at the top of the section to hold the same in place while the elevator is detached.

A further object of this invention is the provision of novel means for opening and closing the jaw slips of tube or pipe gripping means.

Other objects and advantages of this invention will be apparent during the course of the following detailed description.

In the drawings, wherein for the purpose of illustration is shown a preferred embodiment of the invention.

Figure 1 is a plan view of the improved apparatus for handling spider slips for well drilling apparatus, showing the same as it appears during a pipe gripping and supporting operation of the slips.

Figure 2 is a sectional view taken through the apparatus with the parts in the relative position illustrated in Figure 1.

Figure 3 is a fragmentary sectional view showing a spring for normally holding the slip jaws in an inoperative relation with re-

spect to the pipe being lowered or elevated with respect to the well.

Figure 4 is a vertical sectional view taken through details of the invention at the top of the well, showing the jaws or slips in an open relation with respect to the pipe, and in this respect distinguishing from Figure 2.

Figure 5 is a side elevation, partly in section, showing how a portion of the operating means may be moved so as not to interfere with the enlarged joints connecting the pipe sections, and still permit the jaw slips to operate automatically for a gripping operation.

Figure 6 is a plan view of an extensible pipe engaging and operating arm which is used in connection with the operation of the slips.

Figure 7 is a perspective view of one of the jaw slips.

Figure 8 is a plan view of one of the slips.

Figure 9 is a vertical sectional view taken through the upper central portion of the rotary well drilling apparatus, showing the slips in their open relation and in a non-engaging position with respect to the pipe or tubing being lowered, and showing means which will cooperate with the elevator used in lowering the pipe tube or section, to cause an operation of the slips in a gripping relation with the section being lowered at the end of its lowered movement.

Figure 10 is a plan view of the elevator engaging and jaw slip operating part of the invention.

Figure 11 is a fragmentary perspective view of a detail of the apparatus shown in Figure 10.

In the drawings, wherein for the purpose of illustration is shown only a preferred embodiment of the invention, the letter A may generally designate the invention, which includes a base B, which in connection with rotary well drilling apparatus, will be the rotatable platform, upon which a set of slips C are operably disposed, having associated therewith means D to cause a uniform opening and closing jaw gripping and releasing movement with respect to the pipe, tube, or casing section F, as it operates within the base or rotary table B. Means K is used in a

cooperating relation with the means D to cause an automatic closing of the slips upon a pipe section incident to a direct engagement of said means K with the pipe section during an elevating relation, if there is any tendency of the same to lower, as shown in Figure 4, or as shown in Figure 9, the slips may be automatically operated by engagement of said means K with an elevator during the lowering of a pipe section.

10 The base B may be the ordinary rotary table, having the passageway 15 therethrough to receive the pipe sections F. This passageway has a downwardly converging tapered socket 16, in which the slip means C operates during a jaw gripping operation on the pipe F. The upper part of the base B has an enlarged socket 17, which is preferably the square seat ordinarily provided for the polygonal part of the drill stem bushings, as will be well understood by those skilled in the art.

15 While the invention is particularly directed to apparatus for gripping and supporting the sections of drill pipes and the like, it is to be understood that certain features of the invention may be directed to the support of tubing and casing sections of well drilling apparatus.

20 The slip means C preferably consists in the provision of four slips, 19, 20, 21 and 22, each of which is preferably the quadrant of an annular slip. They are of identical formation, and as shown in Figure 7 of the drawings, the outer convex periphery 23 thereof is provided with a longitudinally extending rib 24 which is adapted to slide downwardly or upwardly along a guide-way 27 provided therefor inwardly of the tapered socket 16, as shown in Figure 4 of the drawings. This holds the slips against relative rotation with respect to the rotary table B. In thickness the slips taper in a diminishing dimension downwardly, and the inner concave surfaces 28 thereof may be toothed or otherwise provided with means to insure a non-slip grip upon the pipe section which they are adapted to engage.

25 With reference to the means D which support the slips C for elevated and lowered movement with respect to the socket 16, for the slips 19, 20, 21 and 22 it is preferred to provide shafts 30, 31, 32 and 33; the shafts being rotatably mounted on fixed axes in right angled relation with respect to a line radially intersecting the respective slips midway between the side edges thereof. The operating shafts of opposite slips are arranged 30 parallel, and the shafts are each rotatably supported upon suitable end bearings 35 which may be suitably bolted or otherwise secured upon the top surface of the base or table B. At their proximate ends the shafts 35 are provided with either full or segmental

bevel gears 39 to connect said shafts for synchronous operation.

30 Each of the shafts 30 to 33 inclusive, midway between the ends thereof, is preferably provided with a right angled lever arm 40, keyed therewith as at 41, and extending radially to the respective slips adjacent said shafts. At their free ends the said levers 40 terminate adjacent their respective slips, and are there provided with pairs of links 43, pivoted thereto as at 44, and depending in a downwardly convergent relation towards the slips and being pivoted as at 45 to lugs 46 provided on the top of the slips, as shown in various figures of the drawings.

35 For reasons to be subsequently described, it is considered desirable that the slips be held normally inoperative and in a non-gripping relation with respect to tubing or piping sections F being elevated or lowered with respect to the well. To this end, on each of the shafts 30, 31, 32 and 33, I prefer to provide a spiral spring 50, having one end 51 thereof anchored in an adjacent bearing 35 of the respective shafts, and having the opposite end 52 anchored upon a collar 52 which is adjustably secured at 53 on said shaft. It is readily apparent that the collar 52 should be so adjusted that the expansive action of the spring 50 will tend to rotate the shaft so as to throw the operating lever 40 upwardly and draw the respective slip out of operating relation against the socket 16, that is, to the position illustrated in Figures 4 and 9 of the drawings. It is readily apparent that in this position the slips 19 to 22 inclusive are held out of gripping relation. Inasmuch as the springs 50 are relatively powerful, and to prevent any further upper movement of the slips than is desirable, so that they are still in a position to have the ribs 24 enter their respective grooves 27, I prefer to provide a lateral stop extension 55 upon one of the shafts 32, which engages the top surface of the base or table B when the slips are fully opened, as shown in Figures 4 and 9 of the drawings.

40 For cooperation with the means K, the shaft 32 between the ends thereof and laterally of the lever 40 thereon is provided with a crank 60, having a throw which warrants the recessing of the top of the base or table B as shown at 61 in the drawings.

45 Referring to the means K, the same preferably comprises an extensible arm construction 65, comprising sections 66 and 67; the former of which is telescopic in the latter, and the latter comprises a tube pivoted at 68 upon a bracket 69 which is mounted in a preferably detachable relation upon the top surface 125 of the base or support B. In the tubular section 67 is preferably disposed a spring 70, under compression and urging the sections 66 outwardly therefrom. A connection is established between the telescopic sections 66 and 130

67, which limits the relative extension and collapsed movements thereof, preferably comprising pins 72 rigid on the sections 66 at opposite sides thereof, adapted to slide along the slots 73 at opposite sides of the sections 67, and which slots as to length define the limits of movement of the section 66. The arm construction 65 is radially disposed with respect to the axis of the slip socket 16, and it is also disposed laterally in a non-obstructing relation with respect to the operating arm 40 for the adjacent slip 21.

Special heads 80 and 81 are provided for the outer end of the telescopic arm construction 65, depending upon whether the operation is that of elevating or lowering the drill pipe sections.

If the drill pipe sections are being elevated, the head 80 is used, which as is shown in various figures of the drawings, consists of a substantially U-shaped body 81^a, having the arms 82 and 83 provided in spaced relation, and having surfaces 84 and 85 which are divergent from the arm construction 65 towards the free ends thereof. The body 81^a between the arms is provided with an oppositely extending lug 86, adapted to receive a pin 87 by means of which to pivot the head 80 between the fingers 88 at the bifurcated end of the sections 66 above described. Stop lugs 90 and 91 are provided on the parts 66 and 80 adjacent the pivot pin 87, for abutment to hold the part 80 against dropping below a straight line, or substantially a straight line position.

As to the operation of the part 80, in connection with the means K, during a pipe elevating relation, the pipe F may be drawn upwardly thru the well opening and thru the open slips, and it is preferred that the member 80 rest against the pipe during such withdrawing operation. Due to the pivoting of the member 80 upon the telescoping tube section 66 it may permit large joints, such as shown at 93 in Figure 5 of the drawings, of the pipe F to pass thereby, without interference. When the pipe section has been withdrawn from the well to the extent desired, the action of the elevator permits the pipe line to lower slightly into the well, and due to the tapered relation of the faces 84 and 83 of the pipe gripping fork 80, the latter will frictionally engage in an anti-slip relation against the pipe F and this lowering of the pipe F into the well causes a lowering of the telescope sections of the arm construction 65. Inasmuch as the arm construction 65 rests against the crank 60 of the shaft 32, the said crank will be lowered as the operating means K is lowered, and of course the turning of the crank 60 thru an arc will rotate all of the shafts 30 to 33 inclusive, and thru the arms 40 and links 43, the slips 19 to 22 inclusive will be lowered to a seating relation in their socket 16, and into a gripping relation with

the pipe section F, to engage and grip the same while the pipe section thereabove may be detached at its joint, in an operation which is perfectly well understood in this art. In order that the forked member 80 may be seated accurately on the pipe F to perform the function above outlined, it is preferred that the extensible arm construction 65 have some lateral play upon its pivot 68, that is, by reason of a slightly loose connection.

When lowering a drill stem and adding sections thereto, for the operation of the slips to hold the pipe line or drill stem while a new section is added, the forked head 80 is replaced by the head 81 shown in Figures 9, 10 and 11 of the drawings. This head 81

comprises a concavo-convex body 100, provided with an extension 101 which enters into the socket at the free end of the telescopic outer section 66 of the extensible arm construction 65, and a pin or like means 102 is used to hold the said section 81 in place. The extension 101 may be sufficiently long that it enters the socket at the end of the sliding section 66 so as to firmly anchor the head 81 against pivotal action, so that it will always hold the position shown in Figure 9 of the drawings. The head 81 is such that when placed on the arm construction 65, with the slips in the inoperative relation shown in Figure 9, the head 81 will be spaced from the pipe F'. As the drill pipe or stem is lowered until the elevator M, shown in Figure 9, engages the head 81, the extensible arm construction 65 will be lowered on its pivot 68, and the slip construction will move into a gripping relation with the drill pipe F', as above described.

The head 81 may, or may not, be moved to such an extent that it will engage the pipe F'. It is only essential that the elevator M cooperate with the head 81 to effect a downward movement of the arm construction 65 so as to move the crank 60 of the shaft 32, and operate all of the slips for the clamping effect on the pipe F' above described. The elevator M may then be detached from the pipe line which is being held by the slip, and the weight of the drill stem or pipe line will of course hold the slips in position against the normal action or tendency of the springs 50. When the new drill pipe or section is in position to be added to the drill line, and has been joined thereto, the elevator is placed upon the new pipe section in the proper relation and the entire drill line or stem lifted slightly until the weight of the same is released from the slips sufficient to enable the springs 50 to throw the slips open to the position shown in Figure 9.

It is apparent from the foregoing that a device has been provided which operates automatically upon the means which opens and closes the slips, so as to permit of an automatic closing of the slips by reason of a dropping in the movement of the drill line, if the operation is that of elevating the

drill line to remove sections; or in case the operation is that of lowering the drill line the automatic closing of the slips upon the pipe or drill line is caused by an engagement of the elevator therewith.

5 Various changes in the shape, size, and arrangement of parts may be made to the form of invention herein shown and described, without departing from the spirit of the invention or the scope of the claims.

10 I claim:

1. In apparatus of the class described a base member having a pipe passageway therethrough, a plurality of gripping slips carried thereby and movable to engage and disengage the pipe, means for operating said slips including a crank, and means movably carried by the base and adapted to engage the pipe and the crank to operate the latter for 15 operating the slips into a gripping relation with the pipe upon downward movement of the latter.

2. In apparatus of the class described a base member having a pipe passageway therethrough, a plurality of gripping slips carried thereby and movable to engage and disengage the pipe, means carried by the base for elevating and lowering said slips into or out of gripping relation with respect to the pipe, 20 and an extensible member movable on the base and engaging the pipe and operating with said means to cause the slips to engage the pipe upon a predetermined longitudinal movement of the pipe.

3. In apparatus of the class described a base member having a pipe passageway therethrough, slips operable in the passageway and movable to engage and disengage the pipe, a shaft rotatable upon the base for 25 each of the slips, means gearing said shafts together, means connecting said shafts to the slips to cause the slips to move into and out of gripping relation with the pipe upon rotation of the shafts, and spring means for actuating said shafts in one direction about their axes and normally maintaining the slips out of pipe gripping relation in the base.

4. In apparatus of the class described a base member having a pipe passageway therethrough, slips operable in the passageway and movable to engage and disengage the pipe, a shaft rotatable upon the base for each of the slips, means gearing said shafts together, means connecting said shafts to the slips to cause the slips to move into and out of gripping relation with the pipe upon rotation of the shafts, spring means normally tending to maintain the slips out of pipe gripping relation in the base, one of said shafts having a crank portion thereon between the ends, and a member pivoted on the base and engaging the pipe for permitting an upward movement of the pipe and adapted to move the 60 crank to throw the slips into engaging rela-

tion with the pipe upon a downward movement of the pipe.

5. In apparatus of the class described a base having a pipe passageway therethrough, slips operable in the passageway for gripping and releasing the pipe, a shaft rotatable on the base for each of the slips, lever arms keyed with the shafts extending towards said slips, and links connected with said lever arms and with the slips whereby upon movement of the shafts the slips thru said lever arms and links may be raised and lowered with respect to the passageway thru the base into or out of gripping relation with the pipe received therethrough. 70

6. In apparatus of the class described a base having a pipe passageway therethrough, slips operable in the passageway for gripping and releasing the pipe, a shaft rotatable on the base for each of the slips, lever arms keyed with the shafts extending toward said slips, links connected with said lever arms and with the slips whereby upon movement of the shafts the slips thru said lever arms and links may be raised and lowered with respect to the passageway thru the base into or out of gripping relation with the pipe received therethrough, spring means operating on the shafts to normally raise the slips thereof out of a pipe gripping relation, and means to automatically lower the slips upon a downward movement of the pipe thru the passageway of the base. 80

7. In apparatus of the class described a base having a pipe passageway therethrough, slips operable in the passageway for movement to engage and disengage the pipe, means carried by the base to raise and lower the slips into or out of gripping relation with the pipe, said means including a crank, an extensible arm comprising telescopic members, means pivoting one of said members on the base, spring means urging the other member outwardly from the member which is pivoted on the base, and means carried by the outer member adapted to operate against a pipe which is being elevated from the base passageway, said extensible arm bearing against the crank above mentioned whereby should the pipe be lowered thru the base passageway, the extensible arm operating against the crank will cause the slips to move into a gripping relation with the pipe and hold the same supported upon the base against further lowered movement. 90

8. In apparatus of the class described a base having a pipe passageway therethrough, slips operable in the passageway to engage or disengage the pipe, means resiliently urging the slips to a disengaged relation with the pipe, and a member pivoted on the base and adapted to operate said means to cause an automatic gripping of the slips on the pipe at a predetermined lowering of the pipe. 100

9. In apparatus of the class described a base

- having a pipe passageway therethrough, slips operable in the passageway to engage or disengage the pipe, means resiliently urging the slips to a disengaged relation with the pipe,
- 5 means pivoted on the base and adapted to operate the first mentioned means to cause an automatic gripping of the slips on the pipe at a predetermined lowering of the pipe, said last mentioned means comprising resiliently
- 10 extensible members having a pipe gripping fork pivoted on one end in such a relation that the pipe may be elevated without operating the slips, but upon downward movement will cause the slips to engage the pipe.
- 15 10. In apparatus of the class described a base having a pipe passageway; slips movable in the pipe passageway to engage or disengage the pipe, and means to automatically operate the slips upon a lowering of the pipe
- 20 in the passageway including a member carried by the base and operating against the pipe, and adapted to grip the pipe in a non-slip relation only when the pipe is being lowered.
- 25 11. In apparatus of the class described, a base having a tapered socket therein, a set of slips operable within the tapered socket, means to resiliently urge the slips to an inoperative position with respect to a pipe section
- 30 extending through said socket, and means, including an operating part carried by the base and in direct engagement with such pipe, for permitting an upward movement of the pipe and adapted upon downward movement of
- 35 the pipe to throw the slips into engaging relation with the pipe.
12. In apparatus of the class described, a base having a tapered socket therein, a set of slips operable within the tapered socket,
- 40 means to resiliently urge the slips to an inoperative position with respect to a pipe section extending through said socket, and a resiliently extensible member movable on the base and engaging the pipe and operating with
- 45 said means to cause the slips to engage the pipe upon a predetermined longitudinal movement of the pipe.

CHARLES POWELL.
